CLAIM

The ornamental design for a fixed vehicle hand brake lock, as shown.

DESCRIPTION

FIG. 1 is a perspective view of a fixed vehicle hand brake lock showing my new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The rod shown in broken lines in FIGS. 1, 2, 3, 4 and 6 is for illustrative purposes only and forms no part of the claimed design.

FIG. 6
